Elwin M. John

ATTORNEY.

UNITED STATES PATENT OFFICE.

MAURICE ROTHSTEIN, OF JOHNSTOWN, PENNSYLVANIA.

ROSARY CASE.

Application filed February 5, 1925. Serial No. 7,083.

The invention relates to cases for rosary beads and its object is to provide a simple, neat and efficient case for the reception and enclosure of the rosary beads that is permanently attached to the rosary.

The invention consists in a case fashioned in the shape of a cross to which a rosary is attached in such manner that it may be enclosed in the case when not in use.

10 In the accompanying drawings Figure 1 is a perspective view of the case; Fig. 2 is a similar view with the case opened and Fig. 3 a fractional perspective view of the case with the rosary beads withdrawn therefrom.

15 In the illustrative embodiment of the invention the case 1 is fashioned in the shape of a hollow cross having a reduced extension 2 projecting forwardly from the inner edge of its open front side. A door or cover 3 is 20 hinged to one forward edge of the case, as at 4, and is adapted to pass over the extension 2 so that when it is closed the inner rim 5 of the same will contact with the shoulder or jamb 6 that surrounds the extension 2 on the case.

25 A suitable catch 7 may be engaged on a pin 8 for locking the door to the case. Any suitable means for securing the door in closed position will suffice. A bifurcated lug 9 projects upwardly from the top of the case, and a ring 10 is mounted on the lug for forward and backward movement. An arm 11 is 30 pivotally mounted at one end between the bifurcations of the lug 9 and its outer end is formed for attachment to the rosary beads 35 12. A slot 13 is formed in the top of the case and the extension 2 which extends from the front edge thereof to the lug 9. The arm 11 is adapted to be swung up and down in the slot and is provided at a suitable point with a

40 notch 13^a which permits the wall 14 of the notch to pass under the top and beneath the lug 9 so that the arm may be swung downwardly to a vertical position. When the arm depends in the case it closes the rear portion of the slot 13, a projection 15 on the forward side of the arm closing the forward portion of the slot so that when the door or cover is closed the upper flange of the door overlies projection 15.

50 When the arm is in the case the rosary may

be placed in the case also, thus enclosing the same. The ring 10 remains exteriorly of the case and a watch chain or ribbon may be attached to the ring, the case being deposited in the pocket as is done with a pocket knife 55 that is attached to a watch chain or ribbon. When it is desired to make use of the rosary the door is opened and the rosary taken out and the arm 11 swung upwardly through the slot to an upright position. The cross shaped 60 case then depends from the rosary.

It is apparent that the rosary may be readily removed from or inserted into the case without interfering with any form of support attached to the ring 10, such as a necklace or chain. At the same time the case forms a cross that is permanently attached to the rosary.

The outer face of the door or the sides of the case may be ornamented as desired. Any 70 article adapted to be attached to the pivoted arm and insertable into the case may be substituted for the rosary, and the shape of the case may be varied as desired.

What I claim is:

75 The combination of a cross-shaped hollow case having its front side open, the forward portion of the top, side and bottom walls of the case being reduced in thickness, a bifurcated lug projecting upwardly from the top 80 wall of the case, said top wall having a slot therein extending from the lug to the forward edge of the reduced portion of said wall, an arm pivoted between the bifurcations of the lug and adapted to swing thereon in a vertical plane into the slot, projections upon opposite sides of the arm at its free end disposed in and closing the rear portion of the slot when the arm depends on its pivot, a rosary connected at one end to the free end 90 of the arm and receivable by the case, a cross-shaped door hinged to one wall of the case, and a lateral flange on the door which, when the door is closed, engages the surface of the reduced portions of the walls of the case and 95 covers the portion of the slot therein.

In witness whereof I have hereunto set my hand this 23rd day of January, 1925.

MAURICE ROTHSTEIN.
